HEAD FOR A GOLF PUTTER

Tony J. Vella, 3504 Wesleyan Ave.,
Rockford, Ill. 61108

Continuation-in-part of design application Ser. No.
403,847, Oct. 5, 1973, now Patent No. 235,465.
This application Jan. 16, 1975, Ser. No. 541,603

Term of patent 14 years

Int. Cl. D21—02

U.S. Cl. D34—5 GH

Fig. 1.

Fig. 3.

Fig. 2.

Fig. 4.

Fig. 5.

Fig. 6.

Fig. 7.

FIG. 1 is a top view of a head for a golf putter showing my new design;

FIG. 2 is a front elevation thereof;

FIGS. 3 and 4 are end views as seen, respectively, from the left and right of FIG. 2;

FIG. 5 is a bottom view thereof;

FIG. 6 is a rear view thereof; and

FIG. 7 is a cross-sectional view taken along line 7—7 of FIG. 6.

This is a continuation-in-part of design application Ser. No. 403,847, filed Oct. 5, 1973, and now Pat. No. D. 235,465.

I claim:

The ornamental design for a head for a golf putter, substantially as shown and described.
